SAFETY LOCK

David Yachzel, Chicago, Ill.

Application April 22, 1948, Serial No. 22,569

2 Claims. (Cl. 70—186)

1

My invention relates to safety locks, and pertains to a double feature lock for a door or like closure wherein a latch is provided in combination with key controlled means for locking the latch. In one sense my invention may be considered an improvement or modification of that disclosed in my copending application, Serial No. 673,252, filed May 31, 1946, which resulted in Patent No. 2,563,985.

In accordance with my invention, I provide a key actuated cylinder lock which will secure a bolt actuating device in either locked or unlocked position, the key actuated cylinder lock being disposable on either the same or opposite side of the closure from the control for the bolt actuating device.

Devices embodying my invention are extremely simple in design, inexpensive to construct, rugged and generally satisfactory for the purposes desired.

Various other advantages will suggest themselves to those skilled in the art as the description proceeds.

Referring now to the drawings forming a part of this specification and illustrating a preferred embodiment of my invention:

Fig. 1 is an elevational view of a lock embodying my invention shown mounted on a door or like closure, the latter being shown fragmentarily, the lock being shown in unlocked condition;

Fig. 2 is a similar fragmentary detailed elevation of the operating parts of the lock shown in locked condition;

Fig. 3 is a perspective view of the complete lock;

Fig. 4 is an elevational view showing the rear of the cylinder and parts carried thereby; and

Figs. 5 and 6 are sectional views taken, respectively, along the lines 5—5 and 6—6 of Fig. 2.

The numeral 10 indicates a door or other closure on which is mounted an improved lock 12 embodying my invention. In this case the door closes a passage in a partition or wall, including a door frame 13 on which is mounted a plate 14, to receive or seat the locking elements.

While I have shown my invention as applied to a lock 12 of a basically standard type known as a burglar proof and jimmy proof double feature lock, it should be understood that I do not consider my invention restricted to this type of lock but applicable to a wide variety of other locks for doors and other closures.

In accordance with the usual practice in locks of this general description, the lock 12 comprises a housing 16 for bolt elements (not shown)

which are shot or actuated by means of a shaft or stem 18 and dog 19, the latter being manipulated by means of a knob 20 on the outside of the casing 16. Inasmuch as the bolt mechanism and parts associated therewith controlled by the knob 20 and stem 18 are of standard or other suitable design, it is not considered necessary to show the same here, as such parts are well known in the art. Suffice it to say that the bolt, when actuated by the knob 20, stem 18, dog 19, and parts controlled thereby, projects a locking bar or the like into interengagement with U-shaped loops 21, forming a part of the housing 16 and similar loops 23 formed as part of the door-plate 14.

Secured to the housing 16 is a key actuated lock 25 which is preferably of a standard cylinder type provided with key controlled tumblers or the like. Said cylinder lock 25 may be secured to the casing 16 by means of screws or the like passing through apertures 28 in the housing 16 and engaging tapped holes 29 in the cylinder 25. The cylinder lock comprises a shaft 32 to which is secured a disk 35, said disk carrying an outwardly projecting tongue 37 that serves as an actuating member for a cam about to be described.

On the outside of the casing 16 is secured a circular stem or bearing 40 on which is journaled a cam 42, said cam having a curved face 45 of roughly spiral formation, and a substantially radial face 46 and also a radially projecting finger 48, forming a stop seat 49 on one side thereof and another stop face 50 on the other side thereof. Also projecting from the housing 16 is a limit pin 52.

Secured to the outside of the housing 16 is an elongated housing 53 for a slidable latch or dog 55 controlled by the cam 42. The dog 55 comprises in the main an elongated stem portion 56 and a head portion 58 designed to cooperate with the cam 42. It will be seen that the head portion 58 comprises an outwardly projecting portion 59 which serves in part to retain a helical compression spring 61, while the outer face 63 of the head portion 59 is sloped so that it may be actuated with a minimum of friction by the sloping face of the cam 42.

Preferably formed as a part of the cylinder 25 is an elongated channel-like member 65 which serves as a cover for the housing 53.

The stem or shaft 18 is provided with a diametrical aperture 67, or, in lieu thereof, it may have a recess on opposite sides thereof to receive the dog 55.

It is believed that the operation of my device

will be clear from the above description. The knob 20, operating through the stem 18 and dog 19, serves to actuate the bolt mechanism for the lock in the usual manner. Normally, due to the action of compression spring 61 operating on the projection 59 of the dog 55, said dog 55 will be urged away from engagement with the stem 18, as in the relation shown in Fig. 1, and in this condition the bolt mechanism is free to be locked or unlocked at will.

When it is desired to lock the bolt mechanism in either locked or unlocked relation to the doorplate, a key is inserted in the cylinder lock 25 and the latter is rotated, as a result of which finger 37 will act on the face 46 of the cam 42, as seen in Fig. 1, turning the cam in a counterclockwise direction. The cam face 45 will thus act on the face 63 of the dog 55, urging it toward the left, as shown in the drawings, into the condition shown in Fig. 2 where said dog will interlock with the stem 18, securing it against rotation.

When it is desired to release the bolt mechanism, one turns the cylinder lock in the opposite or clockwise direction, whereupon the finger 37 will engage the face 47 of the cam 42 as seen in Fig. 1, rotating it back to the position of Fig. 1. It will be seen that, as the cam is rotated clockwise, the dog 55 will be moved by the spring 61 toward the right, back to the position shown in Fig. 1 where it is out of locked engagement with the stem 18.

It will be obvious that devices embodying my invention may be constructed in various other ways without departing from the spirit of my invention. Thus, if desired, the cylinder lock may be applied to the opposite side of the lock from the knob 20. Furthermore, my invention may be applied to other types of locks.

Furthermore, if desired, the bolt actuating stem 18 may be incorporated within the circumference of cylinder lock 25 or its housing in the manner shown in my copending application above referred to, instead of being separate therefrom as shown herein. In such case, it would merely be necessary to shorten the dog 58 and the spring 61.

It should be understood therefore that the disclosure is merely exemplary of certain preferred forms and applications of my invention to which I do not intend to be limited.

I claim:

1. In a bolt lock, a casing, a shaft within said casing and rotatable from one position to another position 180 degrees displaced therefrom to project a bolt to extended position and reversely to retract the bolt, said shaft having a diametrically positioned hole therein exteriorly of the casing, a cylinder lock within a housing mounted on said casing, a cam rotatable by said cylinder lock when a key is inserted therein, parallel guide means extending from within the housing of the cylinder lock to adjacent said

rotatable shaft, one of said parallel guide means having an inturned abutment at its end adjacent said rotatable shaft, a dog slidably mounted between said parallel guide means and having a projection at one end forming a follower for said cam, a spring positioned between said abutment on the guide means and said projection on the dog biasing the latter to inoperative position, said cam being effective to shift the dog against the action of said spring into the hole in said shaft in either of the positions of the latter.

2. In a bolt lock, a casing, a shaft within said casing and rotatable from one position to another position 180 degrees displaced therefrom to project a bolt to extended position and reversely to retract the bolt, said shaft having a diametrically positioned hole therein exteriorly of the casing, a cylinder lock within a housing mounted on said casing, a cam rotatable by said cylinder lock when a key is inserted therein, parallel guide means extending from within the housing of the cylinder lock to adjacent said rotatable shaft, one of said parallel guide means having an inturned abutment at its end adjacent said rotatable shaft, a cover plate extending from the housing of the cylinder lock over said parallel guide means to adjacent said rotatable shaft, a dog slidably mounted between said parallel guide means and having a projection at one end forming a follower for said cam, a spring positioned between said abutment on the guide means and said projection on the dog biasing the latter to inoperative position, said cam being effective to shift the dog against the action of said spring into the hole in said shaft in either of the positions of the latter.

DAVID YACHZEL.
